UNITED STATES PATENT OFFICE.

MARTIN C. ALBERTSON, OF GRAY, SASKATCHEWAN, CANADA, ASSIGNOR TO ALBERTSON PRODUCT CO., OF MINNEAPOLIS, MINNESOTA, A CORPORATION OF MINNESOTA.

SHOCK-LOADER.

1,209,534.

Specification of Letters Patent. Patented Dec. 19, 1916.

Application filed March 17, 1914, Serial No. 825,363. Renewed May 17, 1916. Serial No. 98,216.

To all whom it may concern:

Be it known that I, MARTIN C. ALBERTSON, a subject of the King of Great Britain, residing at Gray, in the Province of Saskatchewan and Dominion of Canada, have invented certain new and useful Improvements in Shock-Loaders, of which the following is a specification.

This invention relates to shock loaders and is a divisional portion of my parent application for shock loaders, filed January 10, 1913, Serial No. 741,326.

The principal object of this invention is to associate with the receiving end of the endless shock carrier, a suitable pick-up mechanism which gathers the grain from the ground and deposits it on the carrier, the pick-up mechanism being simultaneously actuated with the actuation of the carrier by the traction of the vehicle on which the carrier is mounted.

A further object of the invention is to associate with the pick-up mechanism a suitable means by which the plane of operation of the pick-up fingers or tangs may be altered in order to adapt the device for handling shocks of various sizes, weights, etc.

Other objects as well as the nature, characteristic features and scope of the invention will be more readily understood from the following description taken in connection with the accompanying drawings and pointed out in the claims forming a part of this specification.

Referring to the drawings: Figure 1 is a top plan view of my improved pick-up mechanism showing the same operatively connected with the shock carrier; Fig. 2 is a fragmentary longitudinal sectional view of the drum showing the fingers or tangs in plan and their connection with the operating element, and Fig. 3 is a fragmentary side elevational view partly in section of my improved device, showing the pickup mechanism raised from the earth and illustrating the manner in which the pickup mechanism is associated with the carrier frame.

In the drawings wherein is shown the preferred embodiment of this invention in order 50 to illustrate the application thereof a por-

tion of the draft beam 5 is provided which is in connection with a portion of a carrier frame 5' said beam having associated therewith a bearing 6 in which is revolubly mounted one end of a shaft 7, said shaft 55 having the intermediate portion thereof depressed to provide a U-shaped structure one arm 8 of which, as previously pointed out is in engagement with the bracket 6 while the opposite arm 9 is in engagement with the carrier frame, while a reciprocable rod 10 is associated with said arm the free end of which is adapted for sliding engagement with said carrier. Tracks 11 of the carrier are arranged above the intermediate portion 60 of the shaft 7, chains 12 riding over said tracks and having engagement with sprocket wheels 13 which are carried by the driven shaft 14, said shaft 14 being supported by the carrier through the medium of bearing 65 arms 15, the latter extending beyond the shaft 14 and provided on the extreme outer ends thereof with sleeves 16, which are engaged with the trunnions 17 of the drum 18.

My improved pick-up mechanism in the present instance comprises the cylindrical drum 18 which is provided with diametrically opposite and uniformly spaced apart apertures 18^a through which are engaged fingers or tangs 19 the latter being engaged 80 with a longitudinally extending bar 20, the tangs on the opposite ends of the bar 20 being in revoluble engagement with links 21 through the medium of the pins 21^a, said links having enlarged ends 22 which are 85 pivotally engaged with similar enlarged ends 23 on shafts 24, said shafts extending through the trunnions 17 and having the extreme outer ends thereof in engagement with levers 25, said levers being each in connection with one end of a rod 26 the opposite end of each of said rods being turned at right angles to the body to provide a hook which is engaged in the apertures 27 of the plate 28.

Mounted on the outer end of each of the trunnions 17 is a sprocket wheel 29 which is fixedly secured thereto and has trained thereabout a sprocket chain 30, said chain being likewise trained over a sprocket wheel 31 100

which is carried by the driven shaft 14. It is therefore seen that when motion is imparted to the shaft 14 through the actuation of the chains 12 that the drum 18 will be 5 revolved causing the tangs 19 to be reciprocated through the apertures in the periphery of the cylinder 18 so as to pick up shocks of grain which lie in its path of movement. It is of course understood that the tangs 19 are 10 fixedly carried by the bar 20 so as to be simultaneously operated with the actuation of said bar when motion is imparted to the tangs on the opposite ends thereof.

In order to retain the shafts 24 against 15 rotation or to alter the position of the enlarged ends 23 which are formed on the inner ends of the shafts 24, the rods 26 are engaged with the desired apertures 27 of the plates 28 thereby causing the pins to engage 20 the enlarged ends 23 of the shafts 24 with the enlarged ends 22 of the links 21 to be brought nearly or be moved farther from a plane passing horizontally through the axis of the drum thereby altering the position 25 of the tangs with respect to the periphery of the drum. This action enables the pick-up mechanism to be adapted for successful operation, according to the size or weight of the shock which is being engaged 30 by the tangs 19.

In Fig. 3 the pickup mechanism is associated with a carrier frame heretofore mentioned, which has mounted therein an endless carrier or conveyer 32 to which motion 35 is imparted by the traction of the vehicle through a mechanism (not shown) the pickup mechanism being shown disengaged from the ground in this view, in which position it is held through the medium of a pawl 40 and ratchet mechanism generally designated 33. The pawl and ratchet mechanism is mounted on the draft beam 5 in proximity to the operator's seat 34, so as to be readily actuated by the operator when so desired. 45 A rod 35 connects the pawl and ratchet mechanism to one end of a bell-crank lever 36, the opposite end being in pivotal connection with the end 8 of the member 7 through the instrumentality of a link 37. 50 A wheel 38 is carried by the end 9 of the shaft 7, so that when the pickup mechanism is disengaged from the earth, movement of the vehicle is permitted in view of the fact that by depressing the shaft 7 intermediate 55 its ends, it is seen that the opposite ends 8 and 9 thereof are offset, thereby causing the wheel 38 to be thrown into engagement with the earth when the pickup mechanism is disengaged therefrom. In operation therefore, assuming that the drum 18 has the tangs 19 thereof in engagement with the earth, the traction of the vehicle causes the drum to be revolved in view of its operative connection with the conveyer or carrier 32,

thereby transporting shocks of grain from 65 the earth to the conveyer 32 upon which they are carried to a predetermined destination. When it is desired to throw the drum 18 out of engagement with the earth, pressure is exerted on the lever of the pawl and 70 ratchet mechanism thereby actuating the bell-crank 36 and causing the shaft 7 to be operated for moving the carrier frame upwardly in a vertical plane thereby causing the wheel 38 to be automatically engaged 75 with the earth in which position it is held from displacement in view of the pawl and ratchet mechanism 33. It will be understood that the above description and accompanying drawings comprehend only the general and preferred embodiment of my invention and that various minor changes in details of construction, proportion and arrangement of the parts may be made within the scope of the appended claims and without sacrificing any of the advantages of my invention.

Having thus fully described my invention what I claim as new and desire to secure by Letters Patent is:—

1. In combination with a vehicle having an endless carrier mounted thereon, a revolute elongated hollow drum extending transversely of said carrier adjacent and in advance of the receiving end, a bar mounted 95 in said drum, having portions extended therefrom to provide tangs, the latter adapted to reciprocate in unison to be extended or retracted relative to the periphery of said drum, a shaft carried by each end of said drum and extending thereto, and having their axes coincident with the axis of said drum, said shaft being in connection with the tang bar at a point eccentric to the axes of the former, means for rotating said shafts 100 independently of said drum, a link carried by each of said shafts on the interior of said drum to reciprocate the tangs as said drum revolves.

2. In combination with a vehicle having an endless carrier mounted thereon, a pick-up mechanism associated with the receiving end of said carrier, said mechanism comprising a hollow drum extending transversely of said carrier and in proximity to 110 said receiving end, a bar in said drum, a plurality of tangs associated with said bar and adapted to reciprocate in unison and to be extended or retracted relative to the periphery of said drum, a shaft carried by 115 each end of said drum and extending thereto, the axes of said shafts being coincident with the axis of said drum, said shaft being in connection with the tang bar at a point eccentric to the axes of the former, means for rotating said shafts independently of said drum, a link carried by each of 120 said shafts on the interior of said drum, each

of said links being in connection with certain of said tangs to reciprocate the latter as said drum revolves, and a driven shaft supported by said carrier and operable thereby, said shaft being in connection with said drum for operating the latter, for the purpose specified.

In testimony whereof I affix my signature in presence of two witnesses.

MARTIN C. ALBERTSON.
